UNITED STATES PATENT OFFICE.

JAMES B. CHRISTIE, OF CORRIGAN, TEXAS.

CHURN.

SPECIFICATION forming part of Letters Patent No. 629,288, dated July 18, 1899.

Application filed April 22, 1899. Serial No. 714,144. (No model.)

To all whom it may concern:

Be it known that I, JAMES B. CHRISTIE, a citizen of the United States, residing at Corrigan, in the county of Polk and State of Texas, have invented certain new and useful Improvements in Churns, of which the following is a specification.

My invention is a churn-motor or means for operating the churn-dasher.

By this invention the dasher is moved in two directions at the same time. It has a vertical motion and a spiral motion both at the same time, because of the fact that the dasher-rod has two spiral grooves running from one end to the other, giving the dasher-rod one turn as it goes up and one turn as it comes down; but by releasing the guides that work in the grooves it has but one motion—a vertical motion.

While this device is primarily intended to operate a churn-dasher, it may also operate a post-hole digger.

In the accompanying drawings, Figure 1 is a perspective view of my invention. Figs. 2, 3, 4, and 5 are detail views. Fig. 6 is a top plan view of the dasher. Fig. 7 is a perspective view of a post-hole digger.

My invention is described as follows:

1 is a beam. 2 are legs inserted in the same. 3 is a vertical longitudinal slot in said beam and in which is journaled a sprocket-wheel 4. 5 are rods set vertically in the forward end of the beam 1, enlarging at their upper ends into head-pieces 6. These head-pieces are secured in proper position by a cross-piece. These rods 5 are held in their vertical positions by braces 7, their upper ends secured to the heads 6 and their lower ends to the beam 1. Between the heads 6 is journaled a sprocket-pulley 8. This pulley is journaled on the crank-shaft 9, and in the U-bend 10 of this crank-shaft is pivoted the upper end of pitman-rod 11, the lower end of which is pivoted in a bearing 12 of a double sleeve-block 13, through the perforations 14 of which are run the standards 5. This sleeve-block 13 has a forward projection 15, in which is firmly secured the churn dasher-rod 16, which passes down through a perforation 17 in the beam 1. This dasher-rod 16 is provided with two spiral slots 18. (See Fig. 4.) This view, Fig. 4, is a cross-sectional view of said dasher-

rod. The forward end of beam 1 is cut away on either side, forming two recesses 19, and leading from the outer faces of these recesses inwardly to perforations 17 are two horizontal perforations 20. These perforations are cone-shaped, their smaller ends terminating in the vertical perforation 17. Fitting in these recesses 19 are hinged two arms 21, each arm provided with a projection 22, cone-shaped and adapted to fit in the perforations 20, their points reaching to and fitting in the spiral grooves 18 of the dasher-rod 16, so that when the dasher-rod moves up it is made, by reason of the grooves 18 and projections 20, to make one revolution and when it moves down to make one revolution. These hinged arms are held in place by a bolt and nut 23 and the other end when closed by bolt and nut 24.

When I want to run the rod 16 up and down without having it revolve, I take away the bolt and nut 24 and let the arm 21 swing out a little until the projections 22 are withdrawn from the grooves 18.

25 25 is a sprocket-chain which passes around sprocket-wheel 4 and sprocket-pulley 8.

The operation of this motor is too apparent to need explanation. The lower end of the dasher-rod 16 is provided with any kind and 80 any number of dasher-wings, and under the beam 1 and so situated that the rod 16 may play up and down therein is set the churn-pail, which may be made after any of the best and most approved styles. When this 85 device is used as a post-hole digger, any spade that is adapted to digging post-holes may be secured to the lower end of the rod 16. Because of the double motion of the rod 16, and consequently of the dasher-wings, the cream 90 is very quickly and very thoroughly churned, and because of the spiral motion of the said rod when a proper spade is attached to the lower end thereof the post-hole is made round and is quickly cut.

Having described my invention, what I claim as new, and desire to secure by Letters Patent, is—

The combination of the beam 1, having feet 2, and longitudinal and vertical slot 3, and 100 recesses 19, perforations 17 and 20; the posts 5, set vertically in the forward end of said beam terminating in heads 6, and secured in position by a cross-piece; braces 7, holding

said posts in a vertical position; sprocket-wheel 4, journaled in slot 3; sprocket-pulley 8, journaled on crank-shaft 9, between heads 6; double sleeve 13, running on posts 5; pitman 11, pivoted to crank-shaft 9, and sleeve 13; spirally-grooved rod 16, passing through perforation 17, its upper end secured in sleeve 13, and its lower end adapted to carry dasher-wings or a spade; arms 21, hinged in recesses 19, and having projections 22, adapted to pass into perforations 20, and their

small ends into grooves 18, of spirally-grooved shaft 16, substantially as shown and described and for the purpose set forth.

In testimony whereof I affix my signature in presence of witnesses.

JAMES B. CHRISTIE.
